Attest.

UNITED STATES PATENT OFFICE

JOHN S. BAKER, OF CHICAGO, ILLINOIS, ASSIGNOR TO COOK ELECTRIC COMPANY, OF CHICAGO, ILLINOIS, A CORPORATION OF ILLINOIS

TELEPHONE PROTECTOR

Application filed April 24, 1929. Serial No. 357,662.

My invention relates to terminal boxes and more particularly to sub-station protectors used particularly for telephone, telegraph or like systems.

- 5 The principal objects of my invention are to provide a terminal box which is compact, durable and simple in construction; to provide improved means in a terminal box for accommodating, distributing, and connecting 10 the conductors leading thereto; to provide an improved mounting, preferably of porcelain, which permits minimum spacing of the terminals accommodating the conductors; to provide improved means for grounding the 15 protective devices associated with a terminal box; and to provide improved means for assuring a grounded connection for the cover of a terminal box, this means acting also as a guide for the cover as it is placed in position 20 over the terminal box.

Other objects and advantages will be apparent from the following description when taken in connection with the accompanying drawings, in which:

- 25 Figure 1 is an elevation of a terminal box mounted in position;

Fig. 2 is a front elevation of one side of the terminal box with the cover shown in dotted lines;

- 30 Fig. 3 is a similar view of the opposite side of the terminal box;

Fig. 4 is also a similar view looking at the device from another side; and

- Fig. 5 is a cross-sectional view taken on 35 line 5—5 of Fig. 4.

The device illustrated in the drawing comprises a horizontal base 1 and a vertical wall 2 which may be integrally formed with the base and made of any suitable insulation material such as porcelain. Protective devices comprising suitable fuses 3 and lightning arresters 4 may be, if so desired, disposed on one side of vertical wall 2. The mounts for such protective devices comprise spring

- 40 conductors 5 for receiving the lower ends of fuses 3. These spring conductors have angularly extending arms 6 disposed against the flat surface of wall 2 and held in position by line terminals 7 and 8. Line terminals 7 and 8 may be of any suitable construction for

receiving the usual line wires 9 and 10 entering the terminal box through openings 11 formed in base 1. Similar spring conductors 12 receive the upper ends of fuses 3 and are likewise held in position by their arms 13' 55 which engage against wall 2 in proper relation with terminals 13 and 14 accommodating wires 15 and 16 leading to the subscriber's line.

Vertical wall 2 may have its upper end 60 formed with a recess 17 adapted to receive a plate 18 which, with arms 13', form a suitable recess for receiving lightning arresters 4. Plate 18 is preferably grounded by means of a rod 20 mounted on wall 2 between the 65 protective devices and extending outwardly from both sides. One end of rod 2 constitutes a terminal 21 for receiving a grounded wire 22. Grounded wire 22 together with subscribers' wires 15 and 16 may leave the 70

terminal box on the side opposite to the line wires through openings 23 formed in base 1. While it is not essential, I prefer, however, to arrange the protective devices in parallel 75 relation in order to secure compact and efficient grouping. Rod 20 extends from one side of wall 2 between lightning arresters 4 and fuses 3. Rod 20 is grounded by ground wire 22 and consequently, a sleeve of insulation 25 is disposed on rod 20 between the 80 fuses. To assist in securing compact arrangement of the live parts on wall 2 and the minimum spacing thereof, between opposite sides of the circuit, wall 2 is provided with a longitudinal slot 26 passing between the line 85

terminals 7 and 8 and the subscriber's terminals 13 and 14. Within predetermined limits, slot 26 prevents the current creeping across these terminals, and consequently, results in permitting these terminals to be 90 spaced closer together on wall 2 than if the slot were omitted.

A suitable cover or enclosure 28 is placed over the whole to enclose the same. Rod 20 is extended far enough from opposite sides 95 of wall 2 to contact with the sides of cover 28 as the cover is placed in position. Being grounded, rod 20 assures that the cover is at all times grounded because it is impossible for the cover to be in position without con- 100

tacting at either end, or both ends, of the said wall, and a cover placed over the whole rod 20. Another advantage of the provision of rod 20 in the form as shown herein is that the cover is guided as it is positioned over the device, thereby preventing accidental contact thereof across the opposite terminals and at the same time assuring that the cover is grounded as soon as it is slipped into position. Cover 28 provides a substantially airtight enclosure for the terminal box. It extends downwardly and tightly fits about the periphery of base 2. The terminal box may be mounted in any suitable way, say by an angle bracket 30 adapted to be bolted to base 1 at 31.

5 10 15

4. A terminal box comprising a base and a wall extending therefrom of insulation material, protective devices carried by said wall terminals at opposite ends of said protective devices for receiving conductor connections said wall having therein a longitudinal slot between said terminals to permit minimum spacing of said terminals on said wall, and cover placed over the whole so as to enclose the same.

5. A terminal box comprising a base and wall extending therefrom of insulation material, protective devices and terminal

15 It is obvious to those skilled in the art
that various detail changes may be made in
the arrangement of the parts carried by wall
2 without departing from the advantages
20 obtained by the provision of grounded rod
20 for guiding and grounding cover 28 as
it is placed in position and the provision of
slot 26 in wall 2 for permitting closer or
25 minimum spacing of the terminals and other
live parts of the circuit.

I claim:

1. A terminal box comprising a horizontal base portion and a vertical wall preferably integral therewith and of insulation material, terminal posts at the upper and lower ends of said vertical wall, protective devices carried by said terminal posts on one side of said vertical wall, the lower terminal posts receiving the incoming conductors on the side 30 of said protective devices and the upper terminal posts accomodating the outgoing conductor connections on the opposite side, grounding means passing through and extending a distance therefrom on each side of 35 said vertical wall, and a suitable cover placed over the whole so as to enclose the same, being guided by and in constant grounded relation with said grounding means.

2. A cable terminal comprising a mounted wall of insulation material, protective devices mounted upon said wall, terminals at opposite ends of said protective devices for receiving the incoming and outgoing conductor connections, said wall having a recess therein, a grounded plate in said recess, lightning arresters disposed upon said wall in recessed relation against said grounded plate, a grounded terminal member connected to said plate, and a cover placed over the whole so as to enclose the same.

3. A terminal box comprising a base and an upwardly extending wall of insulation material, protective devices mounted on one side of said wall, terminals at opposite ends 60 of said protective devices for receiving the incoming and the outgoing conductor connections at the opposite sides respectively of said wall, said wall having therein a longitudinal slot between said terminals, to permit minimum spacing of said terminals on

said wall, and a cover placed over the whole so as to enclose the same.

4. A terminal box comprising a base and a wall extending therefrom of insulation material, protective devices carried by said wall, terminals at opposite ends of said protective devices for receiving conductor connections, said wall having therein a longitudinal slot between said terminals to permit minimum spacing of said terminals on said wall, and a cover placed over the whole so as to enclose the same. 70 75

5. A terminal box comprising a base and a wall extending therefrom of insulation material, protective devices and terminals therefor carried by said wall, said wall having therein a longitudinal slot between said terminals to permit minimum spacing of said terminals on said wall, and a cover placed over the whole so as to enclose the same. 85 80

6. A terminal box comprising a wall, protective devices and terminals therefor carried by said wall, said protective devices including fuses, lightning arresters, and a grounded plate associated with said lightning arresters, a grounded terminal member connected to said plate and passing through and extending a distance therefrom on each side of said wall, and a cover placed over the whole so as to enclose the same, said cover being grounded by substantially constant contact with said grounded terminal member. 95

7. A cable terminal comprising a mounted wall of insulation material, protective devices mounted upon said wall, terminals at opposite ends of said protective devices for receiving the incoming and outgoing conductor connections, said wall having a recess at one end, a grounded plate in said recess and lightning arresters disposed upon said wall in recessed relation against said grounded plate and forming a part of the connections at one end between said protective devices and said terminals. 100 105 110

8. A terminal box comprising a wall, protective devices including fuses and lightning arresters carried by said wall, a cover placed over the whole so as to enclose the same, and a grounded terminal member in grounded relation with said lightning arresters and extending from opposite sides of said wall to contact with and thereby ground said cover. 115

9. A terminal box comprising a wall, protective devices carried by said wall, a grounded terminal member for said protective devices extending a distance therefrom on each side of said wall, and a cover placed over the whole so as to enclose the same, said cover being guided by and in grounded relation with said grounded terminal member. 120 125

In witness whereof, I have hereunto subscribed my name.

JOHN S. BAKER.
